WIRE DRAWING AND SPOOLING SYSTEM

Carroll E. Orr, Orange, N. J., assignor to Syncro
Machine Company, Rahway, N. J., a corpora-
tion of New Jersey

Application January 1, 1942, Serial No. 425,257

21 Claims. (Cl. 205—16)

This invention is broadly concerned with improvements in machines for spooling or coiling strands of any kind such as tape, wire, ribbon, strip, thread and the like, regardless of the material of which such strands are made.

More specifically this invention relates in general to improvements in a mechanism combination comprising primarily a wire drawing machine and a take-up for spooling the wire, including the usual accessories for such a combination.

An object of this invention is to provide a substantially automatically operating system for controlling the operation of a combined wire drawing machine and spooler to perform a novel set of conditions or sequence of operations during the starting and the stopping thereof.

In a general sense with reference to the embodiment herein selected to illustrate the invention it involves the driving of a spooler by means of an electric motor through a magnetic slip clutch the energization of which is controlled or regulated by the formation of a loop in the wire being processed between the wire finishing capstan of a wire drawing machine and the spool. The changes in the size of the loop with changes in tension in the wire operates an induction regulator which controls the supply of energizing current to the clutch. The purpose of this mechanism is to maintain a desired uniform tension in the length of the wire between the finishing capstan and the spool. The fundamental combination of this portion of the mechanism is disclosed in United States Patent No. 2,237,112 issued April 1, 1941. The finishing capstan in such a combination is power driven from a suitable source, as for example in this case from the main motor which drives the drawing blocks of the wire drawing machine. In the operation of such machines the difficulty of breakage of the wire, especially during the starting and stopping of the machine, is encountered by reason of the fact that abnormal stresses are set up in the wire during these periods. In this invention a control system is provided which is interlocked with the controls of the main or wire drawing motor to insure against such breakages.

In accordance with this invention there is provided a mechanism for disconnecting the finishing capstan driving shaft from the power source during stopping. During starting the main motor is energized, bringing the wire drawing machine and the finishing capstan shaft up to speed in the normal manner, during which period the finishing capstan shaft is connected to its power

source. The drive for the spooler is energized at the same time, and a brake associated therewith is released at the beginning of the starting period so that the spooler likewise comes up to

5 normal speed in accordance with usual operations when employing a magnetic slip clutch of the type referred to. At the end of a predetermined period of time of sufficient length to allow the mechanism just described to reach its full normal speed, the current to the magnetic clutch is automatically adjusted to proper operating value. The mechanism then continues to run under the control of an automatic timer, so that at the 10 end of a further predetermined period within 15 which the spool is allowed to fill, the machine is manually or automatically controlled to bring it to a stop.

The automatic means operates to put a capstan timer in operation, which in turn disconnects the 20 finishing capstan from its shaft. The brake is applied to the spooler shaft, a zero speed switch is put into operation, and resistances inserted in the energizing circuit of the magnetic clutch. The spooler then gradually comes to a stop with the 25 main motor circuit under the control of the zero speed switch so that just as or slightly prior to the spooler stopping, the main motor is de-energized. During the decelerating period the relatively massive loaded spool serves to draw 30 wire from the wire drawing machine as required by the spool, and during which period the finishing capstan is driven only by the wire.

As a final phase in stopping the main timer is 35 deenergized and additional resistances put into the energizing circuit of the magnetic clutch so that only a stand-by value of current is supplied to it. After the machine is stopped the capstan timer operates to reconnect the finishing capstan with its driving shaft. The entire mechanism 40 is now at rest and is in condition to be started when a new spool is placed in the machine.

The full details, nature and advantages of the 45 invention will become more apparent from the following detailed description of the embodiment thereof as illustrated in the attached drawings.

This invention resides substantially in the combination, construction, arrangement and relative 50 location of parts, as will be described in detail below.

In the accompanying drawings,

Figure 1 is a side elevational view of the mechanism of this invention showing but a portion of the wire drawing machine;

Figure 2 is an end elevational view of the

mechanism of Figure 1 seen from the plane 2—2 of Figure 1;

Figure 3 is a cross-sectional view taken on the line 3—3 of Figure 1;

Figure 4 is a cross-sectional view taken on the line 4—4 of Figure 1;

Figure 5 is a cross-sectional view taken on the line 5—5 of Figure 1; and

Figure 6 is a diagrammatic circuit illustration of the complete system of this invention.

The right hand end portion of a wire drawing machine is illustrated at 10. One of the capstan assemblies of this machine has been indicated by the reference numeral 11. As shown in Figure 4, this assembly is mounted upon a shaft 12, which is driven by the main driving motor, not shown. Shaft 12 is provided with a sprocket wheel which is connected by a drive chain 13 with another sprocket wheel 14 secured to the clutch part 42 rotatably mounted on the capstan shaft 14. The finishing capstan 15 is secured to the shaft 14, as clearly shown in Figure 4. A switch to be referred to later is normally held closed by means of a roller 16 which engages the wire W in normal operation of the machine.

The wire W passes from the capstan 11 through die 8, and after making several turns about the finishing capstan 15, extends to and partially around a grooved wheel 17 from which it extends back to the finishing capstan 15 and partly there-around so that it may extend therefrom horizontally to the grooved guide wheel 27 in the distributing device 28 of the spooler. The wire passes between a pair of grooved guide wheels 25 in its travel from the finishing capstan 15 to the spooler. The utility of the guide wheels 25 is apparent when it is recalled that the spooler guide wheel 27 reciprocates back and forth axially with respect to the spool as the wire is wound therearound. This is in accordance with common practice in the spooling art.

The wheel 17 is rotatably mounted on an arm 18 which is secured to the shaft 19 of an induction regulator 23. An extension 20 of the arm 18 is provided with a series of adjustable weights 21. A dash pot 22 is connected to the arm 20 so as to dampen the movement thereof. A pair of stops 24 are provided to limit the movement of the arm and the induction regulator within a proper range, as illustrated by means of the dotted positions for the wheel 17 (see Figure 1).

The spool 29 is removably mounted on the spooler shaft 30, which is mounted within the spooler housing 26. The magnetic slip clutch is shown diagrammatically at 31. As disclosed in the before mentioned patent, it consists generally of a magnetizing winding and a pair of aligned disconnected shafts having a pair of discs on the adjacent ends thereof. One of these discs is magnetizable and has a plurality of pole pieces which sweep by a squirrel cage winding or other suitable conductor mounted on the other disc in which eddy currents are generated and thereby providing a magnetic coupling between the two shafts. Thus, as illustrated in Figure 5, one of these shafts is driven from the spooler motor 33 through a suitable sprocket and chain drive 32. The other shaft is connected by means of a pinion 35 and a gear 34 driven thereby to the spooler shaft 30, on which the latter gear is mounted. The distributor 28 is driven from the shaft 30 through the spur gear 28' and the gear 28'', and additional drive mechanism not shown, in accordance with usual practice. The shaft 30 is provided with a pulley 36 which is connected

by a belt to a pulley 37 on the zero speed switch 38. The details of construction of this switch have not been illustrated since there are several well known forms available. The principle of this switch is simply that when the spooler is in motion the switch 38 is closed, but just as the spooler stops, or drops to a predetermined speed, this switch opens.

The spooler shaft is provided with a spring applied brake 39, which brake is released by means of a solenoid 40 (see Figures 1 and 5). Any spring set type of brake is suitable for the purpose, and therefore the details thereof will not be referred to, although a suitable construction is indicated in Figure 1.

Turning now to Figure 4, it will be recalled that the clutch element 42 is driven by the chain 13 and is free for rotation on the shaft 14. The cooperating clutch element 43 is splined to the shaft 14 by means of a key 44 so that it may be slid on the shaft so as to disengage from the clutch part 42. As is shown quite clearly in Figure 3, the clutch part 43 may be slid axially by means of the yoke 45 against adjustable spring 49 by means of a solenoid 48, the linkage system 47 and the shaft 46, to which the yoke 45 is attached. When the solenoid is energized the clutch elements are disengaged.

Reference is now made to Figure 6 wherein the circuit connections for the system are disclosed, and in which are included diagrammatically the various parts previously described in order that the control thereof may be easily understood. A three-phase power supply circuit 50 is controlled by means of a three-poled on and off switch 51. The spooler motor 33 is shown connected by the cable 52 to the switch 51 so that when the switch is closed this motor is energized. The primary of a transformer 53 is connected at one terminal by the wire 54 to one leg of one phase of the power circuit, while the other terminal is connected by wire 55 to the other leg of that phase so that transformer 53 is connected across one phase of this circuit.

One terminal of the secondary of transformer 53 is connected by wire 56 to the relay coil 58 and the motor coil 58' of the main timer 58. This is the timer which shuts the machine down when the spool is loaded. It is of a type very well known in the art employing a motor which may be set to run for any one of a number of time periods of various length within its range. The motor winding 58' is connected through a normally closed limit switch 58'', as shown, which switch controls the timer motor winding 58'. The common terminals of the windings 58'' and 58' are connected by wire 59 to a switch 60 which serves to connect wire 59 to wire 61 when it is closed. This switch is interlocked with the main or wire drawing motor circuit so that when that motor is energized switch 60 closes. Wire 61 returns to the other side of the secondary of transformer 53. The common terminal of the windings of the timer are connected through a switch 61 (which opens at end of timing period) to one terminal of the operating winding of relay 69, the other terminal of which is connected by wire 68 to wire 56 and secondary of transformer 53. The relay 69 operates four switches 69^a, 69^b, 69^c and 69^d.

Wire 54 is connected to one terminal of the winding of relay 55' and to one terminal of the solenoid 48, which operates the capstan clutch previously described. The other terminal of solenoid 48 is connected to one contact of switch 60

controlled by the relay 55' through a thermal overload switch 65 which serves to open the circuit upon overload thereof. The other terminal of switch 66 is connected by wire 67 to the leg of the phase opposite from which wire 54 extended.

The other terminal of the winding of relay 55' is connected by wire 62 to a switch 64^a in the capstan timer, which is connected in series with the switch 64'' and a return wire 68, which goes back to the leg of the phase opposite from which wire 54 extended. The capstan timer 64 is similar to the other timer, in that it has a relay winding 74 and a timer motor winding 75. This timer may be set to operate at different time intervals. One terminal of the winding 74 is connected by wire 73 to the wire 54. The other terminal is connected to one terminal of the winding 75 and by wire 76 to one side of switch 69^a. The other terminal of winding 75 is connected through normally closed limit switch 64' to a tapped point on the winding 74. The switches 64^a and 64'' (which operate at end of timing period), are operated by the timer motor and associated winding 75. The other side of switch 69^a is connected by wire 72 to the opposite leg of the phase to which the wire 54 is connected. Wire 72 also goes to a switch 77 by means of which it may be connected to wire 71 when desired.

Wire 54 is connected by wire 70 to one terminal of the brake solenoid 40. The other terminal of this winding is connected by wire 71 to switch 77 and to one terminal of switch 69^b, the other terminal is connected to wire 72.

One terminal of the secondary of transformer 53 is connected by a wire to one contact of the other pole of switch 77, which is in series with the field windings of the voltage or induction regulator 23, the other field terminal of which is connected to wire 56. The terminals of the movable secondary of the regulator are connected by the wires 79 to an alternating current bridged rectifier 80 employing rectifiers of any suitable type such as the copper oxide plate rectifiers. The output or D. C. terminals of these rectifiers are connected to the wires 81 and 87. Wire 81 is connected to one terminal of the energizing winding 82 of the magnetic slip clutch 31 and its other terminal is connected by wire 83 to one terminal of switch 69^c, and to an adjustable contact on the clutch resistor 84. The other terminal of this resistor is connected by wire 85 to one terminal of the adjustable clutch resistor 86. The other and movable contact of this resistance is connected by wire 87 to the other terminal of the rectifier and to one of the contacts of switch 88. The midpoint of the resistors is connected to the other contact of switch 88. Switch 88 is operated by a coil which is interconnected with the contactors of the main motor control so that switch 88 opens when the last accelerating contactor of the set is closed. The zero speed switch 38 is also interconnected with the main motor control through the holding circuit of the push button controller by means of wire 89 which extends in series with the switch 90 controlled by the traction wire switch operator 16 previously referred to. The other side of this switch is connected by wire 91 to one terminal of the zero speed switch 38 and its other terminal is connected by wire 92 back to the holding circuit. Wires 91 and 92 may be shunted by the switch 69^a.

The exact nature of this invention will now become apparent from the following detailed description of the operation of the entire appa-

tus. It will facilitate an understanding of the circuit of Figure 6 to note that the various parts are shown in de-energized position both with respect to circuit 50 and the main motor controls.

5 In order to set the machine in operation switch 51 is closed. This results in the energization of the primary of transformer 53 and in the energization of the magnetic slip clutch, energizing winding 82 with a current of stand-by 10 value. At this time relay 69 is de-energized so that the circuit for winding 82 from the rectifier 80 is through wire 81, winding 82, wire 83, a portion of resistor 84 depending upon the point to 15 which the movable contact is adjusted, wire 85, closed switch 88, and back through wire 87 to the other side of the rectifier. The stand-by current is of such a low value that the running motor 33 does not cause rotation of the spooler shaft.

20 It is assumed that the machine has been threaded up as indicated in Figure 1, so that the wire W passes through the finishing die 9, around the capstan 15, regulator guide wheel 17, distributor guide wheel 27, and the spool 29, all as 25 previously described. The machine is now ready to be started. In order to start the machine the main or wire drawing machine drive is set in motion by closing a switch which initiates the operation of the main contactors, completes the 30 holding circuit including the wires 89 and 92, and energizes the winding of switch 60 which thereupon closes. The closing of switch 60 causes the energization of the main timer 58 as follows: Current flows from the secondary of transformer 35 53 through wire 56, the windings 58^a and 58^b in parallel, wire 59, switch 60, wire 81, and back to the other terminal of the secondary. Relay winding 69 is energized from the transformer 53, wires 56 and 68, through switch 57 over wire 69 as before. Switches 69^a, 69^b and 69^c close while switch 69^d opens. The opening of the latter switch de-energizes the capstan timer. The closing of switch 69^c places a short circuit across the portion of resistor 84 previously in circuit, 40 thereby increasing the current to the energizing winding of the magnetic slip clutch. The closing of switch 69^b completes the circuit to the solenoid 40 from wire 54, through wire 70, winding 40, wire 71, switch 69^b and wire 72. This releases 45 the brake 39 so that the spooler shaft may start to revolve through the increased energization of the magnetic slip clutch.

50 The closing of switch 69^a short circuits the zero speed switch 38. The de-energization of 55 the capstan timer de-energizes the relay winding 55' by the opening of switch 64^a. Thus switch 66 opens, solenoid 48 is de-energized, and clutch 42 acts so that the capstan 15 is driven from the main motor drive through the chain 13.

60 All of the above operations, of course, take place in much less time than it takes to describe them. Indeed, these operations are substantially simultaneous. At the end of the acceleration period, that is as the entire machine gets up to normal speed, or when the final contactor of the main motor drive closes, the winding of switch 68 is energized opening that switch thereby inserting the portion of resistance 86 to be used into the slip clutch coil circuit so that this clutch 65 is now receiving normal running current. The 70 energization of the clutch winding 82 is now under the control of the voltage regulator 23.

75 The voltage regulator is operated as disclosed in detail in the above mentioned patent, which operation will be briefly reviewed here. As the

tension in the wire W changes, the loop between the finishing capstan 15 and wheel 17 will change in size, causing oscillation of the arm 18 , and hence angular movement of the movable coil of the voltage regulator. As the position of this coil changes the value of the current introduced into it from the field windings will change, in accordance with well known practice, with the result that the energization of winding 82 will vary, so that if the tension on the wire falls off the energization will increase and vice versa. Proper adjustment of this mechanism is accomplished by the proper positioning of the weights 21 , and the dash pot mechanism 22 operates to prevent the abrupt movement of the arm 18 , and hence of the regulator. This mechanism will operate to maintain a substantially constant tension in the wire W as it is fed to the spool.

The machine is now running under normal operating conditions and will continue thus until the spool is loaded, at which time the main timer 58 , or some other manual means, will operate to shut the machine down, in accordance with a sequence of operations now to be described. However, in passing it should be noted that if the wire W should break prior to this time the support for wheel 16 will be gone, with the result that switch 90 will open, breaking the holding circuit for the main motor controller, so that it will stop. At the same time the windings for switches 80 and 88 will be de-energized so that switch 60 opens and switch 88 closes setting up a similar sequence of operations to bring the machine to a stop.

The opening of switch 60 will have the same general effect on the circuits as will the operation of the timer 58 at the end of a predetermined period of time, so that a description of what happens when the latter operates will be sufficient to make it clear as to the same operations which occur when switch 60 opens. We will assume, therefore, that the period of operation under the control of the timer 58 has come to an end, that is when spool 29 is full. Switch 57 opens, breaking the circuit to the relay 69 so that the switches controlled thereby move from the position previously described back to the position illustrated in Figure 6. The opening of switch 69^a takes the short circuit off the zero speed switch 38 . The opening of switch 69^b breaks the circuit to the brake magnet 40 , so that the spring thereof applies the brake to the spooler shaft. The opening of switch 69^c takes the shunt off the portion of resistance 84 in use, reducing the current to the slip clutch winding 82 . The closing of switch 69^d energizes the capstan timer 64 . The energization of this timer completes the circuit to relay winding $55'$. This causes switch 66 to close, energizing the capstan solenoid 48 and disconnecting the clutch parts 42 and 43 . Thus the finishing capstan 15 is disconnected from the main motor drive. The main motor drive is now under the control of the zero speed switch 38 and the spooler is slowing down. At the proper point, preferably just about as the spooler shaft stops rotating, switch 38 opens, with the result that the holding circuit to the main controller is broken and the main motor is de-energized as well as the controls therefor. At the same time, switch 60 opens which de-energizes the main timer 58 . Likewise, switch 88 closes, shunting the portion of resistance 86 in use, and reducing the current to the magnetic clutch to its stand-by value. The capstan timer, in accordance with its adjustment, operates in

due course to de-energize the relay winding $55'$, with the result that switch 66 opens de-energizing capstan solenoid 48 , whereupon the clutch elements 42 and 43 are engaged. Thus the finishing capstan is connected again to shaft 14 by means of force exerted by spring 49 . The machine is now at rest and reset for future starting.

In stopping, as in starting, the sequence of operations above described takes place in less time than it takes to describe them, although in this connection the sequence of operations is spread over a longer period of time in view of the fact that an appreciable period is required to bring the machine to a stop.

With reference to switch 71 , it is to be noted that it is, as termed in the drawings, an operator switch for breaking the direct current circuit from the rectifier, and for energizing the brake as required by certain operating conditions. To do this the switch 71 is thrown to its other position, breaking the circuit to the field of the voltage regulator 23 , and connecting wire 72 directly to wire 71 , thus energizing the brake solenoid 40 in an obvious manner.

The important and basic consideration in connection with this invention is found in the fact that the machine is arranged so that during starting the finishing capstan 15 is power driven and the magnetic clutch is properly energized to take care of the starting load. Likewise, at the instant of starting the spooler brake is released. During stopping the characteristic of the system is that the finishing capstan 15 is disconnected from its driving shaft 14 , so that the inertia of the loaded spool 29 supplies the energy necessary to draw the wire W through the finishing die 9 , it being remembered that the main drive for the wire drawing machine continues at normal operating speed. Thus, the spool is supplied with all the wire that it demands during stopping without excess strain on the wire, thereby minimizing breakage. The spool shaft is braked during stopping, so as to shorten the stopping period, and during this time the effect of the magnetic slip clutch is decreased by inserting extra resistance in the circuit with it. Thus the machine may coast to a stop while maintaining the wire under tension, but not tension sufficient to break it. Finally, the main motor drive is de-energized as the spooler comes to a stop, and then the capstan timer resets the circuits so that the machine is ready for starting.

From the above description it will be apparent to those skilled in the art that the single embodiment of the invention herein disclosed illustrating the principles thereof, does not represent all of the variations of the invention which will readily occur to those skilled in the art in the light of the above disclosure. I do not, therefore, desire to be strictly limited to the disclosure as given for purposes of illustration, but rather to the scope of the claims granted me.

What is claimed is:

1. In a strand spooling machine, the combination including a capstan shaft, power means for driving said shaft, a capstan wheel mounted on said shaft, means for connecting and disconnecting said shaft and power means, spooling mechanism including an independently driven shaft, means for controlling said connecting means to connect said power means to said capstan shaft during the accelerating period of the spooling shaft and for disconnecting said power means from said capstan shaft during the decelerating period of the spooling shaft, and a brake for said

spooling shaft, said brake being actuated by said controlling means to aid in decelerating the spooling shaft and said capstan running free during deceleration.

2. In a machine as described, the combination including a capstan, a capstan shaft for rotatably supporting said capstan, motive means for driving said capstan shaft, means for connecting and disconnecting said motive means and capstan shaft, a spooling shaft, separate power means for driving said spooling shaft, and control means actuated upon energization of said motive means for operating said connecting means to maintain the capstan shaft connected to said motive means during the accelerating period of the spooling shaft, and acting upon de-energization to disconnect said capstan shaft from said motive means during the decelerating period of the spooling shaft.

3. In a machine as described, the combination including a capstan, a capstan shaft for rotatably supporting said capstan, motive means for driving said capstan shaft, means for connecting and disconnecting said motive means and capstan shaft, a spooling shaft, separate power means for driving said spooling shaft, control means actuated upon energization for operating said connecting means to disconnect the motive means from said capstan shaft during the decelerating period of the spooling shaft, whereby the capstan is free and driven only by the wire during deceleration of the spooling shaft, and for connecting the motive means to said capstan shaft at the end of the decelerating period of the spooling shaft.

4. In a machine as described, the combination including a capstan, a capstan shaft for rotatably supporting said capstan, motive means for driving said capstan shaft, means for connecting and disconnecting said motive means and capstan shaft, a spooling shaft, separate power means for driving said spooling shaft, control means actuated upon energization for operating said connecting means to disconnect the motive means from said capstan shaft during the decelerating period of the spooling shaft, whereby the capstan is free during deceleration of the spooling shaft, and for connecting the motive means to said capstan shaft at the end of the decelerating period of the spooling shaft, and means actuated when the spooling shaft comes to rest for operating the connecting means to again connect the motive means to said capstan shaft.

5. In a machine as described, the combination including a capstan, a capstan shaft for rotatably supporting said capstan, motive means for driving said capstan shaft, means for connecting and disconnecting said motive means and capstan shaft, a spooling shaft, separate power means for driving said spooling shaft, control means for said connecting means, means actuated upon energization for operating the connecting means to disconnect the motive means from said capstan shaft during the decelerating period of the spooling shaft, and means operated by the spooling shaft for deenergizing the motive means at or just prior to the stopping of the spooling shaft.

6. In a machine as described, the combination including a capstan, a capstan shaft for rotatably supporting said capstan, motive means for driving said capstan shaft, means for connecting and disconnecting said motive means and capstan shaft, a spooling shaft, power means for driving said spooling shaft, control means for said connecting means, means actuated upon deenergiza-

tion of the spooling shaft, power means for operating the connecting means to disconnect the motive means from said capstan shaft during the decelerating period of the spooling shaft, and means operated by the spooling shaft for deenergizing the motive means at or just prior to the stopping of the spooling shaft, said controlling means operating said connecting means to reconnect the motive means and capstan shaft in preparation for re-starting.

7. In a strand spooling machine, the combination including a capstan, a capstan shaft for rotatably supporting and for driving the capstan, motive means for driving the capstan shaft, means for connecting and disconnecting the motive means and capstan shaft, a spooling shaft, power means for driving the spooling shaft, means for energizing the motive means, the power means and said controlling means, whereby the motive means and capstan shaft are connected during the accelerating period of the spooling shaft, and means operated when the spooling shaft begins to decelerate for operating the connecting means so that the motive means and capstan shaft are disconnected, and means operating upon breakage of the strand for deenergizing the capstan motive means and for operating the connecting means to disconnect it from the capstan shaft during the deceleration of the spooling shaft.

8. In a strand spooling machine, the combination including a capstan, a capstan shaft for rotatably supporting and for driving the capstan, motive means for driving the capstan shaft, means for connecting and disconnecting the motive means and capstan shaft, a spooling shaft, power means for driving the spooling shaft, means for energizing the motive means, the power means and said controlling means, whereby the motive means and capstan shaft are connected during the accelerating period of the spooling shaft, and means operating upon breakage of the strand for deenergizing the capstan motive means and for operating the connecting means to disconnect the motive means from the capstan shaft during the deceleration of the spooling shaft.

9. In a strand spooling machine, the combination including a capstan, a capstan shaft for rotatably supporting and for driving the capstan, motive means for driving the capstan shaft, means for connecting and disconnecting the motive means and the capstan shaft, a spooling shaft, power means for driving the spooling shaft, means for energizing the motive means, the power means and said controlling means, whereby the motive means and capstan shaft are connected during the accelerating period of the spooling shaft, means operating upon breakage of the strand for deenergizing the capstan motive means and for operating the connecting means to disconnect it and the capstan shaft during the deceleration of the spooling shaft, a brake for said spooling shaft, and means for applying the brake to aid in the deceleration of the spooling shaft.

10. In a wire drawing and spooling machine, the combination with a wire drawing machine having a finishing capstan shaft driven thereby, and means for connecting and disconnecting said machine and the capstan shaft for conjoint or independent rotation, of a spooling shaft, separate power means for driving said spooling shaft, and means for controlling said separate power means and said connecting means to de-energize said separate power means and to dis-

connect the capstan shaft from said machine during the decelerating period of the spooling shaft.

11. In a wire drawing and spooling machine, the combination with a wire drawing machine having a finishing capstan shaft driven thereby, and means for connecting and disconnecting said machine and the capstan shaft for conjoint or independent rotation, of a spooling shaft, separate power means for driving said spooling shaft, means for controlling said connecting means, the capstan shaft being connected to said machine during the accelerating period of the wire drawing machine and spooling shaft, and means for operating the connecting means to disconnect the capstan shaft during the decelerating period of said spooling shaft so that the capstan is free of all forces except that it is driven by the wire.

12. In a strand spooling machine, a spooler shaft, a motor for driving said shaft, a magnetic slip clutch through which said motor drives said shaft, an energizing winding for said slip clutch, a capstan, a shaft for the capstan, a power source, a two-position clutch for connecting and disconnecting the capstan shaft and power source, means for operating said two-position clutch, and means actuated when said power source is operative for increasing the energization of the slip clutch winding during its accelerating period, and for decreasing the energization of the slip clutch winding at the end of the accelerating period.

13. In a strand spooling machine, a spooler shaft, a motor for driving said shaft, a magnetic slip clutch through which said motor drives said shaft, an energizing winding for said slip clutch, a capstan shaft, power means for driving the capstan shaft, a two-position clutch for connecting and disconnecting the power means and capstan shaft, means for operating said two-position clutch, means actuated when said power means is energized for increasing the energization of the slip clutch winding, and means for decreasing the energization of said slip clutch winding and for energizing said two-position clutch operating means to disconnect the capstan shaft during the decelerating period of said spooling shaft.

14. In a strand spooling machine, a spooler shaft, a motor for driving said shaft, a magnetic slip clutch through which said motor drives said shaft, an energizing winding for said slip clutch, a capstan shaft, power means for driving the capstan shaft, a two-position clutch for connecting and disconnecting the power means and capstan shaft, means for operating said two-position clutch, means actuated when said power means is energized for increasing the energization of the slip clutch winding, a brake for said spooling shaft, and means for decreasing the energization of said slip clutch winding and for energizing said two-position clutch operating means to disconnect the capstan shaft and for applying the brake during the decelerating period of said spooling shaft.

15. In a strand spooling machine, a spooler shaft, a motor for driving said shaft, a magnetic slip clutch through which said motor drives said shaft, an energizing winding for said slip clutch, a capstan shaft, power means for driving the capstan shaft, a two-position clutch for connecting and disconnecting the capstan and its shaft, means for operating said two-position clutch, means actuated when said power means is ener-

gized for increasing the energization of the slip clutch winding, means controlled by the strand for controlling the slip clutch winding for varying its energization to maintain a substantially uniform tension in the strand between the capstan and the spooling shaft, and means for actuating the clutch operating means to disconnect the capstan shaft during deceleration of the spooler shaft.

16. In a wire drawing and spooling machine, the combination with a wire drawing machine having a finishing capstan shaft driven therefrom, and means for connecting and disconnecting the capstan shaft for conjoint or independent rotation, of a spooling shaft, a separate power means for driving said spooling shaft, and means for controlling said connecting means to disconnect the capstan shaft during the decelerating period of the spooling shaft, said connecting means automatically reconnecting the capstan shaft at the end of the decelerating period so that it is ready for the next start.

17. In a strand spooling machine, the combination including a capstan shaft, a capstan wheel mounted on said shaft, a first power means, means for connecting and disconnecting said power means and said shaft, spooling mechanism including a spool shaft, a second power means for driving said spool shaft, means for operatively connecting and disconnecting said second power means to and from said spool shaft, and means for controlling both of said connecting means to disconnect said first power means from said capstan shaft and said second power means from said spool shaft during the decelerating period of the spool shaft and for connecting said first power means to said capstan shaft at the end of the decelerating period of said spool shaft.

18. In a strand spooling machine, the combination including a capstan shaft, a first power means, a capstan wheel mounted on said shaft, means for connecting and disconnecting said shaft and power means, spooling mechanism including a spool shaft, a second power means for driving said spool shaft, means for operatively connecting and disconnecting said second power means to and from said spool shaft, and means for controlling both of said connecting means to connect said first power means to said capstan shaft during the accelerating period of the spool shaft, and said second power means to said spool shaft, and for disconnecting said first power means from said capstan shaft during the decelerating period of the spool shaft.

19. In a strand spooling machine, the combination including a capstan shaft, a first power means, a capstan wheel mounted on said shaft, means for connecting and disconnecting said first power means and said capstan shaft, spooling mechanism including a spool shaft, a second power means for driving said spool shaft, means for operatively connecting and disconnecting said second power means to and from said spool shaft, means for controlling said connecting means to connect said first power means to said capstan shaft during the accelerating period of the spool shaft, and for disconnecting said first power means from said capstan shaft during the decelerating period of the spool shaft, and a brake for said spool shaft, said brake being applied to aid in decelerating the spool shaft.

20. A combination of the type described comprising a power driven wire drawing machine having a capstan and driving shaft therefor, means including a clutch for driving said shaft

from said drawing machine, a spooling machine including a spool shaft, a motor for said spool shaft, a clutch for connecting said motor to said spool shaft, a brake for said spool shaft, and control and operating means for de-energizing said motor, disconnecting the clutch thereof to free said capstan shaft, disconnecting the clutch for said spool shaft and applying said brake whereby said capstan shaft runs free during the decelerating period of said spool shaft.

10

21. In the combination of claim 20, a magnetic clutch for the spool shaft, and means operated by the wire for controlling the energization of said clutch whereby a substantially uniform tension is maintained in the wire between the drawing machine and the spool shaft.

CARROLL E. ORR.
